INTERNAL COMBUSTION ENGINE

Filed July 16, 1924

UNITED STATES PATENT OFFICE.

EVERETT R. BURTNETT, OF LOS ANGELES, CALIFORNIA, ASSIGNOR OF ONE-HALF TO
HOMER A. BRUNELL, OF LOS ANGELES, CALIFORNIA.

INTERNAL-COMBUSTION ENGINE.

Application filed July 16, 1924. Serial No. 726,322.

To all whom it may concern:

Be it known that I, EVERETT R. BURTNETT, citizen of the United States, residing at Los Angeles, in the county of Los Angeles and State of California, have invented certain new and useful Improvements in Internal-Combustion Engines, of which the following is a specification.

My invention relates generally to internal combustion engines, and more particularly to engines of the two stroke cycle type wherein pumping cylinders are utilized for the precompression of gaseous fuel and for the forcing of said precompressed fuel into the combustion chambers.

The principal objects of my invention are to generally improve upon and simplify the construction of the existing forms of two stroke cycle engines, to provide an engine of the character referred to having a plurality of combustion cylinders arranged in pairs with the members of each pair connected at their head ends by a common clearance compression and combustion chamber, to arrange at one end of the cylinder block or row of cylinders a series of gaseous fuel pumping and precompression cylinders, the latter being connected by gaseous fuel transfer ducts to the combustion cylinders.

As a result of my improved arrangement of cylinders and the connections between the pistons in said cylinders and the crank shaft of the engine, the torque resulting from the expansion of the ignited gaseous fuel charges and the axial rocking couple of the combustion units are transmitted to the rear portion of the crank shaft and the pumping torque and couple developed within the pumping cylinders and their connections is transmitted to the forward portion of the crank shaft.

A further object of my invention is to provide in an engine of the character referred to a crank shaft having cranks arranged in proper angular positions to bring about the proper movements of the pistons within the cylinders, to provide said crank shaft with five bearings, and to equip the rear portion of said crank shaft with counterbalancing weights that tend to cause said crank shaft to operate with practically no vibration and without "whip" at all speeds, thereby insuring an even flow of power while the engine is in operation.

With the foregoing and other objects in

view, my invention consists in the features of construction and combination and arrangement of parts hereinafter more fully described and claimed, reference being had to the accompanying drawings, in which— 60

Figure 1 is a vertical section taken lengthwise through the center of an engine of my improved construction;

Figure 2 is a diagrammatic view which graphically illustrates the relative positions 65 of the cranks of the crank shaft of my improved engine.

Referring by numerals to the accompanying drawings, 10 designates a cylinder block that is preferably formed with connected chambers 11 in its walls for the circulation of a fluid cooling medium, and formed in the rear portion of said block are six combustion chambers that are arranged in pairs, thereby forming practically three power units. Chambers 12 and 13, forming one pair, are arranged adjacent to the center of the block, chambers 14 and 15 forming the next pair being located to the rear of chambers 12 and 13, and the third pair of chambers 16 and 17 being located at the rear end of the block. Formed in the front portion of the block and in front of the pair of combustion chambers 12 and 13 are three gaseous fuel pumping and precompression chambers 18, 19 and 20. All of the chambers just described are preferably arranged in a row with their axes parallel. 75 80 85

Secured in any suitable manner on top 90 of block 10 is a head block 21 having a chamber 22 through which may be circulated a fluid cooling medium, and formed in the under side of the front portion of this head block are three shallow recesses 23, 95 24 and 25 that coincide with and constitute compression clearance chambers for the gaseous fuel pumping and precompression chambers 18, 19 and 20, respectively.

Formed in the under side of the intermediate portion of head block 21 is a pocket or recess 26 that connects and provides a common clearance compression and combustion chamber for the pair of combustion chambers 12 and 13. A similar chamber 27 105 that is formed in the under side of the head block 21 connects the head ends of combustion chambers 14 and 15, and provides a common clearance compression and combustion chamber therefor. A third shallow 110

chamber 28 that is formed in the under side of the rear portion of head block 21 connects the head ends of chambers 16 and 17 and provides a common clearance compression and combustion chamber for said chambers 16 and 17. Seated in head block 21 and preferably at points above the combustion chambers 12, 14 and 16 are spark plugs 29, the terminals of the electrodes of which project, respectively, into the common clearance chambers 26, 27 and 28.

Leading from clearance chamber 23 above pumping chamber 18 to transfer inlet ducts 30 that are formed through the wall of block 10 and which communicate with the intermediate portion of combustion chamber 12 is a gaseous fuel transfer duct 31. A similar duct 32 leads from the side of clearance chamber 24 above pumping chamber 19 to precompressed gaseous fuel inlet ports 33 that are formed through the wall of block 10 and which open into the intermediate portion of combustion chamber 14. A third precompressed gaseous fuel transfer duct 34 leads from the side of clearance chamber 25 above the pumping chamber 20 to the intermediate portion of combustion chamber 16.

Thus it will be seen that through the arrangement of the ducts just described pumping cylinder 18 at the front end of the engine block functions for the power unit comprising the cylinders 12 and 13; pumping cylinder 19 functions for the power unit comprising the cylinders 14 and 15; and the third pumping cylinder 20 functions for the unit comprising the cylinders 16 and 17.

Formed through the wall of cylinder block and at points intermediate the ends of the chambers 18, 19 and 20 are gaseous fuel inlet ports, such as 35, that are connected to a suitable source of gaseous fuel supply, for instance a carburetor. Formed through the wall of block 10 and leading outwardly from the intermediate portions of the power unit combustion chambers 13, 15 and 17 are exhaust ports, such as 36. All of the ports just described are positioned so that they are wholly uncovered and open only when the pistons that operate within the respective cylinders are at the lower to outer ends of their travel.

Block 10 surmounts a crank case member 37 and formed in the end portions of the latter are bearings 38 for a crank shaft 39. Formed within this crank case member between pumping cylinder 20 and combustion cylinder 12 between the combustion cylinders 13 and 14, and between the combustion cylinders 15 and 16 are bearings 40 for said crank shaft. Thus the crank shaft is provided with five bearings, thereby insuring minimum vibration during operation.

The forward portion of the crank shaft

is provided with three cranks or throws 41, 42 and 43, the same being arranged 120° apart, and said cranks being located, respectively, beneath or in line with the axes of the pumping cylinders 18, 19 and 20. Pistons 44, 45 and 46 that are arranged for reciprocation, respectively, within chambers 18, 19 and 20 are connected by suitable connecting rods, such as 47, to the cranks 41, 42 and 43, respectively. Arranged for reciprocatory movement within the combustion chambers 12 and 13 are pistons 48 and 49, respectively, said pistons being connected by suitable connecting rods, such as 50, to a crank 51 that is formed on crank shaft 39 to the rear of crank 43, said crank 51 being of sufficient length to accommodate the two connecting rods 50. Projecting from the central portion of crank 51 diametrically across the axis of the crank shaft is an arm 52 on the end of which is arranged a counterbalancing weight 53.

A crank 54 that is similar to crank 51 is arranged beneath or in line with the combustion chambers 14 and 15, and suitable connecting rods 55 connect said crank 54 with pistons 56 and 57 that are arranged, respectively, in the chambers 14 and 15. Projecting diametrically across the axis of the crank shaft from the center of crank 54 is a counterbalancing weight carrying arm 58.

A crank 60, similar to cranks 51 and 54, is arranged beneath cylinders 16 and 17, and the pistons 61 and 62 that are arranged, respectively, in said chambers 16 and 17 are connected to said crank 60 by suitable connecting rods 63. Projecting from the central portion of crank 60 diametrically across the axis of the crank shaft is a counterbalancing weight carrying arm 64.

Cranks 51, 54 and 60 are arranged 120° apart, and with respect to cranks 41, 42 and 43 crank 51 is arranged diametrically opposite or 180° from crank 41; crank 54 is located diametrically opposite or 180° from crank 42; and crank 60 is located diametrically opposite or 180° from crank 43 (see Figure 2).

As a result of this crank arrangement, the pistons 48 and 49 in combustion cylinders 12 and 13 travel simultaneously with and directly opposite to pumping piston 44, and this action is also true of pistons 56 and 57 in the combustion cylinders 14 and 15, and pumping piston 45, and likewise the pistons 61 and 62 in combustion cylinders 16 and 17 and the pumping piston 46. As each pumping piston approaches and passes low center, the corresponding gaseous fuel inlet ports are uncovered, thereby admitting a charge of gaseous fuel, and on the upward or inward stroke of the pumping piston this gaseous fuel charge is compressed in the corresponding clearance chamber in the head block and in the transfer duct leading

from said clearance chamber. As each pair of pistons within the combustion chambers approach and pass their low centers, the corresponding precompressed gaseous fuel 5 inlet ports and exhaust ports are simultaneously opened, thereby admitting a charge of precompressed gaseous fuel into the first chambers of each pair, and the in-rush of this fuel charge upwardly through the chamber 10 into which the precompressed fuel is admitted and thence through the common clearance chamber in the head block and thence downwardly through the rear chamber of each pair to the exhaust ports leading 15 therefrom effects a discharge of the products of combustion remaining in the connected combustion chambers from the previously ignited fuel charge.

On the succeeding upward stroke of the 20 pair of pistons within the combustion chambers to which the precompressed fuel charge was admitted, as just described, said gaseous fuel will be compressed in the upper portions of the connected chambers and in 25 the common clearance chamber therefor. As each pair of combustion pistons pass their high centers or immediately thereafter, the compressed gaseous fuel charge in the common clearance chamber above said pistons 30 will be ignited by a spark produced between the terminals of the electrodes of the corresponding spark plug, and the expansion following combustion of the charge thus ignited will force the pistons downward 35 or outward on their power stroke. Inasmuch as the cranks that are associated with the three power units of the engine, which power units comprise the three pairs of connected combustion chambers, are arranged 40 120° apart, the crank shaft receives three power impulses during each revolution, thereby insuring a practically even flow of power output, and as the three cranks for the three power units form the rear portion 45 of the crank shaft, said rear portion will receive all the expansion torque and axial rocking couple that is developed in the engine during operation. Inasmuch as three pumping cylinders are arranged at the forward 50 end of the engine and in front of the power units, the pumping torque and couple will be impressed only upon the forward portion of the crank shaft or that portion to which the pistons within the pumping cylinders 55 are connected.

The arrangement of five main bearings 60 for the crank shaft, the relative angular arrangement of the cranks of said shaft, the relative positions of the pumping cylinders with respect to the series of cylinders forming 65 the power units, and the counterbalancing of that portion of the crank shaft to which the power units are connected, all combine and cooperate to eliminate vibration 70 in the crank shaft during operation and

to enhance the smooth running action of the engine.

It will be understood that minor changes in the size, form and construction of my improved two stroke cycle internal combustion 70 engine may be made without departing from the spirit of my invention, the scope of which is set forth in the appended claims.

I claim as my invention:

1. In a two stroke cycle internal combustion engine, three power units, each of which comprises a pair of combustion cylinders connected at their head ends by a common clearance chamber, a series of three pumping cylinders arranged in front of and 80 in row with the cylinders forming the power units, and means whereby each pumping cylinder functions for the precompression and pumping of gaseous fuel into one cylinder of each pair of connected combustion 85 cylinders.

2. In a two stroke cycle internal combustion engine, three power units, each of which comprises a pair of combustion cylinders connected at their head ends by a common 90 clearance chamber, a series of three pumping cylinders arranged in front of and in row with the cylinders forming the power units, means whereby each pumping cylinder functions for the precompression and 95 pumping of gaseous fuel into one cylinder of each pair of connected combustion cylinders, pistons arranged for operation within all of the cylinders, a crank shaft to which 100 said pistons are connected, the cranks to which the pistons in the pumping cylinders are connected being arranged 120° apart, and the cranks to which the pistons of the power units are connected being arranged 105 120° apart.

3. In a two stroke cycle internal combustion engine, three power units, each of which comprises a pair of combustion cylinders connected at their head ends by a common clearance chamber, a series of three pumping cylinders arranged in front of and 110 in row with the cylinders forming the power units, means whereby each pumping cylinder functions for the precompression and pumping of gaseous fuel into one cylinder 115 of each pair of connected combustion cylinders, pistons arranged for operation within all of the cylinders, a crank shaft to which said pistons are connected, the cranks to which the pistons in the pumping cylinders 120 are connected being arranged 120° apart, the cranks to which the pistons of the power units are connected being arranged 120° apart, and the respective cranks for the 125 pistons of the power units occupying radial planes that are diametrically opposite or 180° from the corresponding cranks for the pistons in the pumping cylinders.

4. In a two stroke cycle internal combustion engine, a plurality of combustion 130

- 4
- cylinders arranged in pairs with the members of each pair connected at their head ends by a common clearance chamber, a series of pumping cylinders arranged in front of and in row with the combustion cylinders, a precompressed gaseous fuel duct leading from the inner end of each pumping cylinder to one of the combustion cylinders of each pair, and the other cylinder 10 of each pair of combustion chambers being provided with an exhaust port.
5. In a two stroke cycle internal combustion engine, a plurality of combustion cylinders arranged in pairs with the members of each pair connected at their head ends by a common clearance chambers, a series of pumping cylinders arranged in front of and in row with the combustion cylinders, a precompressed gaseous fuel duct 15 leading from the inner end of each pumping cylinder to one of the combustion cylinders of each pair, the other cylinder of each pair of combustion chambers being provided with an exhaust port, pistons arranged for 20 operation within all of the cylinders, and a crank shaft to which all of said pistons are connected.
6. In a two stroke cycle internal combustion engine, a plurality of combustion cylinders arranged in pairs with the members of each pair connected at their head ends by a common clearance chamber, a series of pumping cylinders arranged in front of and in row with the combustion cylinders, a precompressed gaseous fuel duct 25 leading from the inner end of each pumping cylinder to one of the combustion cylinders of each pair, the other cylinder of each pair of combustion chambers being provided with an exhaust port, pistons arranged for 30 operation within all of the cylinders, and a crank shaft to which all of said pistons are connected.
7. In a two stroke cycle internal combustion engine, a series of cylinders arranged in row, certain of the cylinders at one end of the row functioning as gaseous fuel precompression and pumping cylinders, the remaining cylinders in the row being arranged in pairs with the members of each pair connected at their head ends by a common clearance chamber, said pairs of connected cylinders functioning as combustion cylinders, and which are served by the pumping cylinders at the end of the row, pistons arranged for operation within all 35 of said cylinders, and a crank shaft to which all of said pistons are connected.
8. In a two stroke cycle internal combustion engine, a series of cylinders arranged in row, certain of the cylinders at one end of the row functioning as gaseous fuel precompression and pumping cylinders, the remaining cylinders in the row being arranged in pairs with the members of each pair connected at their head ends by a common clearance chamber, said pairs of connected cylinders functioning as combustion cylinders, and which are served by the pumping cylinders at the end of the row, pistons arranged for operation within all 40 of said cylinders, a crank shaft to which all of said pistons are connected, and five main bearings for said crank shaft.

In testimony whereof I affix my signature.

EVERETT R. BURTNELL.
